UNITED STATES PATENT OFFICE.

EDWIN B. STIMPSON, OF BROOKLYN, E. D., NEW YORK.

DESIGN FOR AN ORNAMENTAL BORDER.

SPECIFICATION forming part of Design No. 12,058, dated December 7, 1880.

Application filed September 13, 1880. Term of patent 3½ years.

To all whom it may concern:

Be it known that I, EDWIN B. STIMPSON, of Brooklyn, E. D., in the county of Kings and State of New York, have invented a new and original Design for an Ornamental Border, of which the following is a specification.

The accompanying printed illustration represents a face view of my newly-designed border.

10 This invention relates to a new and original design for a border, which may be stamped or otherwise cut in paper, thin sheet metal, or any other suitable fabric or material, and is designed to be used for the lining or trimming of paper boxes, bird-cages, frames, for trimming shelves, ornamenting ceilings, or any other purpose for which it may be adapted, as the judgment of the user may indicate. I propose, however, to employ it chiefly in the 15 form of a stamped paper border.

In the printed illustration filed herewith, A represents a punched scallop having, by preference, its edges formed of waved or broken lines.

20 A lozenge-shaped or diamond-shaped figure is formed beneath the scalloped border A, and composed of an inner set of dots or perforations, b', describing a lozenge, an outer set, b², whose lines are, respectively, parallel to those of the set b', and a surrounding series of dashes, a, and dots, b. The dashes a may be of lozenge-shape or oval, if desired.

25 At the center of the diamond-shaped figure formed by the inner set, b', and the outer set, b², of perforations there is placed a small diamond-shaped figure. Immediately above the point of intersection of the lines of dots b and dashes a of the consecutive lozenge or diamond shaped figures there is placed a dot

or perforation, and immediately below the 40 said point of intersection there is placed another dot. The lines of dots and dashes intersect each other at points nearly opposite adjacent points of the lozenge-shaped figures.

C are stars arranged in the angles formed 45 by the intersecting lines of dots and dashes a b, and embellished with central radii, c, converging toward a central point or perforation, e.

The bounding-line of the star is a series of 50 dots or perforations, and the radial figures c are preferably elongated or diamond-shaped figures, whose central longitudinal lines intersect at the center of the star.

Between the star and the nearest point of 55 intersection of the lines of dots b and dashes a there is placed a substantially heart-shaped figure, as shown.

I claim—

1. The design for a border having scallops 60 A, the diamond-shaped or lozenge-shaped figures B, formed of the lines of dots or perforations b' b², and the surrounding series of dots b and dashes a, substantially as shown.

2. The design for a border having the loz- 65 enge-shaped figures B, formed of sets of dots or perforations b' b², and the surrounding se- 70 ries of dots b and dashes a, and stars C, formed with a bounding-line of dots or perforations, and embellished by the radially-arranged fig- ures c, substantially as shown.

In testimony whereof I affix my signature in presence of two witnesses.

EDWIN B. STIMPSON.
